CLAIM

We claim the ornamental design for a harness relief step, as shown and described.

DESCRIPTION

FIG. 1 is a perspective view of a harness relief step showing our new design, shown in a stored position of use; FIG. 2 is a bottom plan view thereof; FIG. 3 is a top plan view thereof; FIG. 4 is a left side elevation view thereof; FIG. 5 is a right side elevation view thereof; FIG. 6 is a front elevation view thereof; FIG. 7 is a rear elevation view thereof; FIG. 8 is another perspective view thereof, shown in a partial deployed position of use; and, FIG. 9 is another perspective view thereof, shown in a deployed position of use.

The dash-dot-dash broken lines illustrate boundaries of the claim and form no part of the claimed design. The even dash-dash broken lines illustrate features of the harness relief step that form no part of the claimed design. The zig-zag broken lines forming a separation in FIG. 9 illustrate break lines of a symbolic break in length and form no part of the claimed design. The appearance of any portion of the harness relief step between the break lines forms no part of the claimed design.
